UNITED STATES PATENT OFFICE.

HERBERT G. SMITH, OF DUNDAS, ONTARIO, CANADA.

DESIGN FOR A POOL-TABLE POCKET.

40,286.

Specification for Design.

Patented Oct. 5, 1909.

Application filed June 1, 1909. Serial No. 499,607. Term of patent 7 years.

To all whom it may concern:

Be it known that I, HERBERT G. SMITH, a subject of the King of Great Britain, residing at Dundas, in the county of Wentworth and Province of Ontario, Canada, have invented a new, original, and ornamental Design for Pool-Table Pockets, of which the following is a specification, reference being had to the accompanying drawing, forming part thereof.

The figure is an elevation showing the design of the front face of the pocket.

I claim—

The ornamental design for a pool table pocket, as shown.

HERBERT G. SMITH.
